UNITED STATES PATENT OFFICE.

JOHN T. H. DEMPSTER, OF SCHENECTADY, NEW YORK, ASSIGNOR TO GENERAL ELECTRIC COMPANY, A CORPORATION OF NEW YORK.

VAPOR ELECTRIC APPARATUS.

1,074,253.

Specification of Letters Patent. Patented Sept. 30, 1913:

Original application filed April 27, 1904, Serial No. 205,107. Divided and this application filed August 14, 1905. Serial No. 274,212.

To all whom it may concern:

Be it known that I, JOHN T. H. DEMPSTER, a citizen of the United States, residing at Schenectady, in the county of Schenectady and State of New York, have invented certain new and useful Improvements in Vapor Electric Apparatus, of which the following is a specification.

My present invention relates to certain improvements in means for starting and operating mercury vapor apparatus such for example as mercury vapor lamps, rectifiers, or the like.

In carrying my invention into practice I mount the lamp or other device so as to be carried on a pivot and provide electromagnetic means for tilting the device on this pivot in order to start the same.

The features of novelty characteristic of my invention are pointed out in the appended claims. The invention itself, however, will be better understood by reference to the following description taken in connection with the accompanying drawings, 25 in which—

Figure 1 represents a perspective view of an apparatus embodying my invention, Figs. 2 and 3 are diagrams representing one method of using such apparatus, and Figs. 30 4 and 5 a modified method of using the apparatus.

The mercury lamp or similar device which is to be started by the use of my invention may be used either on constant potential or 35 constant current circuits. It may assume various forms, as for example that shown in Fig. 1, in which the tube of glass 1 or other material constitutes the container or envelop of the lamp. Pockets 2 and 3 are 40 formed near opposite ends of the lamp and are provided with leading-in conductors 4 and 5. These pockets are filled with mercury so as to constitute electrodes and sufficient mercury is provided so that when the 45 lamp is in a horizontal position the mercury completely bridges over the space between the electrodes and forms a conducting ribbon or body as indicated at 6. The lamp 1 is mounted by means of clips 7 and 8 on a beam 9. This beam has a cross-arm 10 by means of which it is pivoted between two standards 11 and 12 carried by a supporting base 13. A solenoid 14 carried by the base 13 is provided with a movable core

15 adjustably connected to one end of the beam 9. This solenoid is connected in series with the lamp. A second solenoid 16 is provided with a core 17 adjustably connected to the opposite end of the beam 9 and is connected across the two electrodes or terminals of the lamp. This solenoid may or may not be used in the operation of the lamp as desired. A dash pot 18 is connected between the beam 9 and the base so as to prevent too rapid tilting of the lamp. An arm 19 60 adjustably secured to the cross-arm 10 carries a weight 20 which may be adjusted along the arm 19. The position of the arm 19 and the weight 20 may be varied to automatically bring the lamp 1 into desired 70 position with the parts in a state of equilibrium.

When the apparatus is to be used with the series solenoid 14 alone the weight 20 is adjusted so that the lamp is brought into 75 a horizontal position when out of service, in which case the mercury in the lamp forms a conducting bridge between the electrodes. This horizontal starting position of the lamp is shown in Fig. 2 in which 21 and 22 represent the mains by which current is supplied to the lamp. As soon as the current is turned on to the lamp the series solenoid 14, becoming energized, pulls down one end of the beam carrying the lamp and causes 80 mercury to flow into the lower end of the lamp and thus break the bridge or ribbon of mercury between the electrodes. The position thus assumed by the lamp is shown in Fig. 3. The arc thus struck between the 90 broken ends of the ribbon is continued between the mercury in the pockets 2 and 3 until the current is interrupted for any reason, whereupon the parts return by gravity to the starting position. The dash pot 95 18 causes the tilting of the lamp to be slow and thus provides a more favorable condition for starting than is present when an abrupt rupture of the mercury bridge or ribbon takes place.

Instead of starting with the lamp in a horizontal position and with the mercury forming a bridge between the electrodes, I am enabled by the use of the shunt solenoid 16 to start with the lamp in an inclined position as represented in Fig. 4. In this instance the counterweight 20 is adjusted so as to bring the lamp into the desired starting

100

105

position. In this case the starting position, as shown in Fig. 4, is similar to the running position shown in Fig. 3. The high resistance shunt solenoid 16, however, when current is applied to the lamp in the starting position, upon becoming energized, tilts the lamp to a horizontal position, as indicated in Fig. 5, whereupon mercury flows between the electrodes 2 and 3 forming a conducting bridge 23 short circuiting the solenoid 16. The solenoid 14, then being traversed by a largely increased current, and assisted also by gravity, causes immediate return of the lamp to the starting position shown in Fig. 4. The mercury bridge 23 is thus broken and the mercury arc is started in the lamp. In the running position the series solenoid 14 is far stronger than in the starting position so that the solenoid 16, being weaker than in the starting position, because of the voltage drop in the steadyng resistance 27 and coil 14, is of insufficient strength to tilt the lamp again, whereupon the lamp continues to run with the parts in the same position as represented in Fig. 4.

It is obvious that various modifications may be made in the embodiment of my invention without departing from the spirit thereof, for which reason I do not wish to be limited to the exact details shown and described.

This application is a division of my pending application for Letters Patent, Serial No. 205,107, filed April 27, 1904.

What I claim as new and desire to secure by Letters Patent of the United States, is,

1. A vapor device comprising a movable container, normally separated electrodes or contacts in said container and included in the main operating-circuit of the device, one of such electrodes being a conducting liquid, and automatic means for moving the container so as to make and break conductive connection between the said electrodes.

2. A vapor device comprising a movable container, normally separated electrodes or contacts in said container and included in the main operating-circuit of the device, a conducting liquid or fluid in said container, and automatic means for moving the container so as to make and break conductive connection between said electrodes.

3. A vapor device comprising a movable container, the said device being adapted to operate in a position other than horizontal, normally separated electrodes, and a con-

ducting liquid in said container included in the main operating-circuit of the device, and automatic means for tilting the device so as to make and break conducting connection between the electrodes.

4. A mercury-vapor lamp comprising a movable container for mercury, normally separated electrodes in said container included in the main operating-circuit of the lamp, and automatic means for moving the container so as to make and break metallic connection between the said electrodes.

5. A mercury-vapor lamp comprising a movable container for mercury, the said lamp being normally tilted from a horizontal position and being adapted to operate in an inclined position, and automatic means for tilting the lamp so as to make and break metallic connection between the 75 electrodes.

6. A mercury-vapor device comprising a movable container for mercury, normally separated electrodes in said container, and included in the main operating circuit of the device, and means operated by the main current adapted to move said container so as to make and break metallic connection between the electrodes.

7. A mercury-vapor device comprising a movable container for mercury, normally separated electrodes in said container, and included in the main operating circuit of the device, and means operated by the main current adapted to move said container so as to make and break metallic connection between the electrodes, and to maintain the rupture of the internal circuit of the device through the mercury until the main current is interrupted.

8. A mercury-vapor device comprising a movable container for mercury, normally separated electrodes in said container, and included in the main operating circuit of the device, and automatic means for moving the container so as to make and break metallic connection between said electrodes, such means including a magnet-coil in series with the device, whereby the said coil acts as an inductive resistance in the main circuit.

In witness whereof I have hereunto set my hand this 4th day of August, 1905.

JOHN T. H. DEMPSTER.
